UNITED STATES PATENT OFFICE

102,193

DESIGN FOR A SHOE OR SIMILAR ARTICLE

André Perugia, Paris, France

Application November 7, 1936, Serial No. 65,763

Term of patent 3½ years

To all whom it may concern:

Be it known that I, André Perugia, a citizen of the Kingdom of Italy, residing in Paris, France, have invented a new, original, and ornamental Design for a Shoe or Similar Article, of which the following is a specification, reference being had to the accompanying drawing, forming part thereof;

I claim:

The ornamental design for a shoe or similar article, substantially as shown.

ANDRÉ PERUGIA.
